Inventor
Isaac P. Cornog

By his attorney

UNITED STATES PATENT OFFICE.

ISAAC P. CORNOG, OF PHILADELPHIA, PENNSYLVANIA.

RATCHET-WRENCH.

SPECIFICATION forming part of Letters Patent No. 333,199, dated December 29, 1885.

Application filed November 11, 1885. Serial No. 182,406. (No model.)

To all whom it may concern:

Be it known that I, ISAAC P. CORNOG, of the city and county of Philadelphia, and State of Pennsylvania, have invented an Improvement 5 in Ratchet-Wrenches, of which the following is a specification.

My invention has reference to ratchet-wrenches; and it consists in certain improvements, fully set forth in the following specification and shown in the accompanying drawings, which form part thereof.

The object of my invention is to form a cheap, durable, and practical ratchet-wrench capable of being instantly set for right or left hand working.

The main feature of the invention consists in the simple and effective construction of the double pawl, which is adapted to work in connection with the ratchet-teeth formed on the 20 socket-shaft.

In the drawings, Figure 1 is a plan view of a ratchet-wrench embodying my improvement, and Fig. 2 is a sectional elevation of same on line *xx*.

25 A is the handle, and is provided on one end with the hub or bearing section B.

C is a ratchet-wheel, the teeth *c* of which are made with faces equally inclined, substantially as shown. The said ratchet-wheel is provided 30 with the square socket G, preferably made somewhat tapering, and the shaft section D, which is furnished with an annular groove, E, so located as to come within the hub B, in which said shaft D is journaled.

35 F is a screw-stud, which passes through the hub B and fits into the groove E. The shaft D is extended through to the back of the wrench, and is provided with the pivot-screw H, which may be used when the wrench is 40 employed for drilling, it then acting as a feeding device as well as a center. It is evident, however, that the extension of the shaft D and the centering-screw H might be dispensed with, so far as the ratchet-wrench proper is concerned.

I is the pawl, and is provided with the two legs J, uniting in a body having a slot, L, and is pivoted to the handle A by a stud, M, which passes through the slot and is riveted over the 50 same, to prevent its displacement. Prior to securing the pawl in position a spring, O, is

inserted in a recess, N, on the under side of the pawl, and, pressing against the stud M, tends to force the pawl toward the ratchet-wheel. This stud M may be cast integral with 55 the handle or may be riveted in place. The pawl, between the legs J and the pivot M, is notched, as at K K, formed substantially as if two holes were drilled through the said pawl and cut into each other, thus insuring the 60 tongue *k* extending down somewhat between the said holes or notches.

P is a stud or projection formed on the handle, and projects up into the holes or notches K of the pawl.

65 From the foregoing it is seen that the pawl may be shifted so that the lug P shall project into either of the holes K, thus making the wrench right or left handed, and the said stud performs the function of preventing the pawl 70 from being carried around upon the ratchet-wheel during operation, it acting as a stop for the pawl in either direction, according as to which leg is in operating position.

While I prefer the construction shown, I do 75 not limit myself to the details thereof, as they may be somewhat modified without departing from my invention.

Having now described my invention, what I claim as new, and desire to secure by Letters 80 Patent, is—

1. The combination of the handle of a ratchet-wrench having a pawl-stop, P, with the ratchet-wheel journaled upon an end of said handle and provided with the nut or drill receiving hole, and the pivoted pawl I, having the two legs J J, notches or holes K K, separated by the tongue *k*, and a spring to press 85 said pawl toward the ratchet-wheel, substantially as and for the purpose specified. 90

2. The combination of the handle A, having hub B and studs M and P, with ratchet-wheel C, having shaft D, furnished with annular groove E, and, further, with the nut or drill receiving hole G, screw F, working in said 95 annular groove, pawl I, having two legs, J J, notches or holes K K, and slot L and spring O, substantially as and for the purpose specified.

3. The combination of the handle A, having 100 hub B and studs M and P, with ratchet-wheel C, having shaft D, furnished with annular

groove E, and, further, with the nut or drill receiving hole, center and feed screw H, screw F, working in said annular groove, pawl I, having two legs, J J, notches or holes K K, 5 and slot L and spring O, substantially as and for the purpose specified.

4. The handle A, having hub B, in combination with ratchet-wheel C, having shaft D, furnished with annular groove E, journaled 10 in said hub, screw F, secured in said hub and

fitting into said groove, center and feed screw H, carried by said shaft, and a pawl to connect the ratchet-wheel with the handle, substantially as and for the purpose specified.

In testimony of which invention I hereunto 15 set my hand.

ISAAC P. CORNOG.
